UNITED STATES PATENT OFFICE

ARVID BJORKLUND, OF MINNEAPOLIS, MINNESOTA

LATHE

Application filed March 23, 1927. Serial No. 177,583.

My present invention relates to lathes and has for its object to provide an extremely simple and highly efficient lathe designed to be knocked down so that the same may be packed in a very compact space for shipping or storage.

To the above end, generally stated, the invention consists of the novel devices and combinations of devices hereinafter described and 10 defined in the claims.

In the accompanying drawings, which illustrate the invention, like characters indicate like parts throughout the several views.

Referring to the drawings:

15 Fig. 1 is a view of the improved lathe in front elevation with some parts broken away and sectioned;

Fig. 2 is a view in end elevation with some parts broken away;

20 Fig. 3 is a view in transverse vertical section taken on the line 3—3 of Fig. 1;

Fig. 4 is a view principally in transverse vertical section taken on the line 4—4 of Fig. 1;

25 Fig. 5 is an enlarged plan view of the tailstock with some parts broken away and sectioned, and also showing portions of the bed of the lathe;

Fig. 6 is a detail view with some parts sectioned on the line 6—6 of Fig. 5;

Fig. 7 is a fragmentary perspective view of one of the frame end members;

Fig. 8 is a fragmentary detail view with some parts sectioned on the line 8—8 of Fig. 35 1;

Fig. 9 is a perspective view of the shelf removed from the lathe;

Fig. 10 is a view showing a modified tailstock; and

40 Fig. 11 is a detail view principally in section taken on the line 11—11 of Fig. 10, on an enlarged scale.

The frame of the lathe comprises a pair of independent end members 12, each of which 45 comprises a pair of legs rigidly connected at their upper ends, and further connected by a horizontal, inturned, bed-supporting web 13 having a pair of deep notches 14, which extend longitudinally of the lathe.

50 A bed 15 is detachably supported on the

frame end members 12, projects outward thereof at both ends, and has in its top a central longitudinal groove 16 which extends the full length thereof. The front and rear members of the bed 15 are connected by end 55 and intermediate crosstie members 17 integrally formed therewith below said bed, and having relatively wide and deep notches directly under the groove 16. Formed with the bottom of the bed 15, at the ends thereof, are 60 horizontal, inturned webs 18 that further rigidly connect the front and rear members of said bed, rest on the webs 13 of the end members 12 and have deep notches 19. These notches 19 extend transversely of the lathe 65 and intersect the notches 14, as best shown in Fig. 8. Nut-equipped bolts 20 are inserted through the notches 14 and 19, at their points of intersection, and rigidly but detachably secure the bed 15 to the frame end members 70 12. The frame end members 12 are rigidly but detachably connected by a pair of nut-equipped crosstie rods 21. The legs of the frame end members 12 are countersunk at 22 to receive the outer ends of the crosstie rods 75 20 and their nuts so that they do not project outward of said legs.

A headstock 23, a tailstock 24 and tool rest 25 are mounted on the bed 15 and are adjustably and detachably secured thereto by 80 clamping plates 26 and cooperating nut-equipped bolts 27. Said clamping plates 26 span the groove 16 and bear against the under side of the bed 15, as best shown in Figs. 2, 3, and 4. The longitudinal edges of the bed 85 15, at the groove 16, are chamfered and the ends of the bearing plates 26 are reversely chamfered and have longitudinal sliding contact therewith. The bolts 27 extend through aligned apertures in the clamping plates 26 and the bases of the headstock 23, tailstock 24, and tool rest 25. The nut members of the bolts 27 for the tailstock 24 and tool rest 25 are provided with lever handles 90 28 by which they may be operated. The aperture in the base of the tool rest 25 is in the form of a slot 29 which permits compound turning and bodily adjustment of said tool rest on the bed 15.

The headstock spindle 30 is driven from 100

an electric motor 31 by a variable speed device which includes a belt 32 that runs over a pair of aligned step cone pulleys 33 and 34, the former of which is on the spindle 30 and the latter of which is on the shaft of the motor 31. Said motor 31 is bolted to a shelf 35 located directly under the headstock 23, and which shelf has a wide upstanding arm 36 that is detachably secured to the bed 15 by upper and lower nut-equipped bolts 37 and 38, respectively. The upper bolt 37 is passed through a bore in the adjacent cross-tie member 17 and a vertical slot 39 in said arm. The bolt 38 is passed through a bore in a lug 40 on the arm 36 and a vertical slot 41 in a lug 42 on the bed 15. Obviously, the slots 39 and 41 permit the shelf 35 to be vertically adjusted to vary the tension on the belt 32. The headstock 23 is positioned on the bed 16 outward of the respective end members 12 and its live center is shown as directly applied to the inner end of the spindle 30 and the pulley 33 is directly applied to the other end thereof outward of said end member with the bearing 25 for the spindle 30 between said live center and pulley. By thus mounting the headstock 23 with its pulley 33 outward of the respective end of the bed 16 and aligned with the pulley 34 on the motor 31, the belt 32 is entirely outward of the bed 16 and headstock 23 where the same may be out of the way and may be easily changed on the cone pulleys 33 and 34 to vary the speed of the spindle 30. By applicant's construction a face plate, not shown, 35 may be readily applied by any suitable means to the outer end of the spindle 30, see Fig. 2, for holding work to be turned of such diameter that it cannot be mounted over the bed 16.

It will be noted that the apertures in the shelf 35 for bolts 43, which detachably secure the motor 31 to said shelf, are in the form of radially arranged slots 44. A tailstock spindle 45 is mounted for endwise rotary movement in its bearing 46 on the tailstock 24 and is provided with a radially projecting cam stud 47 which works in a spiral cam slot 48 in the bearing 46. Said cam stud 47 is provided with a nut-acting member 49 for securing the spindle 45 in its bearing 46. This 45 nut-acting member 49 affords a hand piece by which the cam stud 47 may be moved in the cam slot 48 to impart compound rotary and endwise movement to the spindle 45. Obviously, endwise adjustment of the spindle 55 moves its center pin toward and from the headstock 23.

Referring now to the modification shown in Fig. 10, the tailstock 50 is provided with a spindle 51 mounted in a bearing 52 on said tailstock for endwise adjustment. The bearing 52 is longitudinally split and provided with a clamping bolt 53 having a hand piece-equipped nut 54 for frictionally contracting said bearing onto the spindle 51 to hold the same where set. For moving the spindle 51

endwise to cause its center pin to enter a piece of work, a cam 55 is pivoted to the rear end of the bearing 52 for action on the rear end of said spindle and provided with a hand piece 56 for operating the same.

From the above description it is evident that the various parts of the lathe may be very easily and quickly separated and the parts assembled so as to assume a very compact form for the purpose of shipping or storing. By vertically adjusting the shelf 35, the tension of the belt may be varied, at will, and by mounting the tailstock 24 on the bed 15 for longitudinal adjustment, the pulley 33 may be properly aligned with the pulley 34. The tailstock 24 may be bodily adjusted toward and from the headstock 23 and the spindle 45 may be endwise adjusted by means of the nut-acting member 49 to cause its center pin to enter a piece of work, or to withdraw the same therefrom. After the spindle 45 is properly set, the same may be secured by simply tightening the nut-acting member 49.

By shifting the belt 32 on the step cone pulleys 33 and 34 the speed of the spindle 20 may be varied, at will.

What I claim is:

1. In a lathe, a frame having a bed extending outward of one end thereof, a headstock mounted on the bed outwardly of the frame, a bracket suspended from the bed below the headstock, an electric motor mounted on the bracket, pulleys on the headstock and motor outward of the bed, and a belt arranged to run over the pulleys.

2. The structure defined in claim 1 in which the bracket is mounted for vertical adjustment in respect to the headstock.

3. In a lathe, a frame having a bed extending outward of one end thereof, a headstock mounted on the bed outwardly of the frame and having a live center directly applied to the inner end of its spindle and a pulley directly applied to the other end thereof outward of the bed and a bearing for the spindle between the live center and pulley, a bracket suspended beneath the bed below the headstock, an electric motor mounted on the bracket and having a pulley aligned with the pulley on the headstock, and a belt arranged to run over said two pulleys.

In testimony whereof I affix my signature.

ARVID BJORKLUND.
